UNITED STATES PATENT OFFICE.

SAMUEL J. KING, OF BELTON, SOUTH CAROLINA.

WRITER'S ARM-REST.

1,113,020.

Specification of Letters Patent.

Patented Oct. 6, 1914.

Application filed February 24, 1914. Serial No. 820,791.

To all whom it may concern:

Be it known that I, SAMUEL J. KING, a citizen of the United States, residing at Belton, in the county of Anderson and State of South Carolina, have invented new and useful Improvements in Writers' Arm-Rests, of which the following is a specification.

This invention has reference to writers' arm rests, and it proposes, briefly, an improved device of the general character stated which may be readily applied to the forearm adjacent to the elbow for the purpose, primarily, of acting as a support for the side muscles thereof.

More especially, however, the invention contemplates the provision of an arm rest which is so constructed as to enable it to be applied like a bandage, whereby the muscles referred to may be positively bound up, with varying degrees of tightness, and thus given a more positive support than has heretofore been possible with analogous devices.

An embodiment of the invention is illustrated in the accompanying drawing, whereof:—

Figure 1 is a perspective view showing its application and mode of use; Fig. 2 is an enlarged bottom plan view; and Fig. 3 is a longitudinal sectional view on line 3—3, Fig. 2.

Referring more particularly to the said drawing, the improved device consists, briefly, as shown, of two main parts, namely, the arm rest proper A, and the attaching means B therefor. The former part is composed of an elongated body 5 made of a single ply or thickness of some suitable flexible textile or other material in the center of which body is arranged a pad 6 of any desired size and shape. This pad is preferably constructed of sheet rubber of the required thickness to support the elbow of the wearer above the writing surface, and it is vulcanized to the outer face of the body 5 at its edges, the portion 7 of such body directly above the pad being cut away, as will be understood from Figs. 1 and 3. In the construction illustrated, the pad is of a circular or disk-like form, and the opening 7 in the body, beneath which it is disposed is likewise circular, but of slightly less diameter than the pad itself. The attaching means B is applied to the inner end of said body, and as herein shown, such means consists of a strap 10 of elastic fabric stitched

at one end to the body and provided at its other end with a ring 11, with which ring is engaged the central portion of a second strap 12, likewise of elastic fabric. The two branches 13 of the strap 12 are caused to diverge by being led in opposite directions, and to each is secured a button 14, or other like fastener, and, also, a complementary clasp or loop 15. The buttons 14 are located at the ends of the branches 13, and the loops 15 are stitched or otherwise connected to said branches beyond said buttons, in such a way as to enable them to be swung toward and from, for engagement with or disengagement from, the buttons.

In attaching the device, the body part A is applied against the under surface of the forearm at or close to the elbow, with the pad 6 directly beneath the point of the bone 75 that constitutes the pivot about which the arm is to swing, the free or outer end of said body part being situated at the outer side of the arm. The two end portions are then drawn upward against the adjacent 80 side portions of the arm, like a bandage, and the attaching means B then passed across the upper surface of the arm and the branches 13 engaged with the outer or free end portion by means of the fasteners 14 85 and 15. This end portion may be drawn as tightly as desired against the arm, and will be retained in such position by reason of the elasticity of the straps 10 and 12, thereby effectively supporting the adjacent 90 arm muscles, and, consequently, avoiding danger of writers' cramp, it being understood that the relative lengths of the straps should be such as to cause them to normally exert some tension upon the end portion in 95 question, when connected thereto. Also, owing to the attachment of the loops to the strap branches 13 at the rear of the buttons, the afore-mentioned end is enabled to be inserted therebetween to a greater or less extent, according as may be desired, so that an adjustment of the body to compensate for different conditions is insured.

I claim:—

1. A writer's arm rest comprising a bandage-like body portion consisting of a single thickness of flexible material adapted to be applied against the under surface of the fore-arm at the elbow; means for adjustably drawing the ends of said body directly 105 toward each other against the adjacent side surfaces of the arm, to bind up the adjacent 110

side muscles, to different degrees of tightness; and an arm-supporting pad secured to the central portion of the under surface of said body and adapted to lie beneath the point of the elbow.

2. A writer's arm rest comprising a bandage-like body portion consisting of a single thickness of flexible material adapted to be applied against the under surface of the fore-arm at the elbow; elastic means permanently connected to one end of said body and adapted for adjustable and removable connection to the other end thereof, to draw said ends directly toward each other and against the adjacent side surfaces of the arm, with varying degrees of tightness; and an arm-supporting pad secured to the central portion of the under surface of said body and adapted to lie beneath the point of the elbow.

3. A writer's arm rest comprising a bandage-like body portion consisting of a single thickness of flexible material adapted to be

applied against the under surface of the forearm at the elbow; an elastic strap permanently connected to one end of said body and having a terminal ring; a second elastic strap passed through said ring and having its central portion engaged with the same, the two ends of the said second strap being adapted for adjustable and removable connection to the other end of said body, to draw the ends of the body directly toward each other and against the adjacent side surfaces of the arm, with varying degrees of tightness; and an arm-supporting pad secured to the central portion of the under surface of said body and adapted to lie beneath the point of the elbow.

In testimony whereof I have hereunto set my hand in presence of two subscribing witnesses.

SAMUEL J. KING.
